THOMAS BURDICK, OF MONTROSE, CALIFORNIA, ASSIGNOR OF ONE-HALF TO ADOLF MILAR, OF LA CRESCENTA, CALIFORNIA

MITER BOX

Application filed January 8, 1931. Serial No. 507,413.

This invention relates to mitering guides, and has for an object the provision of a miter box of such relatively small and compact design that it is readily portable, permitting its use by a workman in relatively inaccessible and unhandy locations and under such circumstances that a miter box constructed in accordance with more conventional design could not be employed.

10 A more detailed object is the provision of a mitering guide in which the saw-guiding means is mounted upon a relatively small and compact bed adapted to be engaged upon a piece of lumber which is to be cut according to a predetermined angle and held thereupon in proper operative position by one hand of the operator, while he manipulates with the other hand the saw which is guided by the mitering device, in such a manner that the timber is cut at the desired angle.

20 Another object is to provide an improved design of saw-guiding means for a miter box.

A still further object is to provide a mitering guide having the above described characteristics, and which is adapted to have the guiding means adjusted with respect to the bed about a horizontal axis, as well as about a vertical axis, whereby double angles 30 may accurately be cut.

The invention possesses other objects and advantageous features, some of which, with those enumerated, will be set forth in the following description of the invention's particular embodiment which is illustrated in the drawings accompanying and forming a part of the specification.

Referring to the drawings:

Fig. 1 is a perspective view of the mitering guide of my invention operatively associated with a timber, in such a manner as to guide a saw for the purpose of cutting the timber according to a predetermined angle.

Fig. 2 is a top plan view, the direction of view being indicated by the arrow 2 of Fig. 1, and with a portion of the figure broken away to reduce its length.

Fig. 3 is a longitudinal vertical sectional view taken upon the line 3—3 of Fig. 2, with the direction of view as indicated. A por-

tion of this figure is broken away to reduce its length.

Fig. 4 is a view similar to Fig. 3, but showing the saw guide swung about a horizontal axis, so as to vary the angularity with respect to the vertical of a cut made by a saw guided thereby.

Fig. 5 is another view similar to Fig. 3, but showing the saw guide swung in the opposite direction about its horizontal axis of adjustment.

The conventional miter box, whereby the ends of pieces of timber may be accurately cut according to a predetermined angle or predetermined angles, is of relatively heavy and clumsy design, requiring that it be mounted upon a bench, sawhorse, or other suitable support, in order to permit of its use. This disadvantage of the ordinary miter box precludes its being used to advantage under many circumstances, such, for example, as where a workman is required to work in relatively inaccessible and awkward locations. Such a condition frequently arises during the construction of a building when the roof rafters and other members are being cut and assembled. Because of the fact that a workman under such circumstances cannot have a work bench or a sawhorse easily available, he is required either to cut the timbers without the assistance of a miter box or to descend from his elevated position, carrying with him the timber to be cut, and after having cut the timber, climb back, carrying the timber with him in order to assemble it in its proper location.

My invention seeks to overcome this disadvantage of the conventional miter box by providing a mitering guide which is of such compact, light, and simplified construction that it may easily be employed by a workman at the location where the timbers are to be assembled. With this object in view, the bed 11 of my improved mitering guide, instead of being a trough or channel construction adapted to be mounted upon and rigidly secured to a suitable support, utilizes the timber 12, upon which the cutting operation is to be performed, as its support, it being intended that the operator shall hold the

mitering guide in proper operative position with respect to the timber, with one hand, while he manipulates with the other hand the saw, which is guided by the miter device in such a manner as to cut the timber according 5 to the desired angle.

The bed 11 comprises a relatively elongated strip 13, preferably of metal and having a flange 14 extending downwards therefrom along the forward edge of the strip. Hence, 10 the strip 13 and flange 14 cooperate to define therebetween a right angle adapted to be engaged upon the upper forward corner 16 of the timber 12. The flange 14 is provided with extensions 17 at spaced intervals 15 therealong, preferably in the form of removable fingers of metal detachably secured to the flange 14 and/or to the strip 13 as by one or more machine screws 18. However, 20 inasmuch as the extensions 17 are intended to cooperate with the flange 14 in holding the bed 11 accurately in parallelism with that face of the timber 12 with which the flange 14 is in engagement, the extensions 17 are 25 so constructed and mounted that their after faces lie flush with the after face of the flange 14, this being accomplished by notching either the flange 14 to receive the extensions 17 therein, or by notching the upper ends of each extension to receive the flange 14 therein, or by notching both.

A sector plate 21 is mounted for pivotal movement about a vertical axis adjacent one end of the bed 11. The means whereby the 30 sector plate 21 is mounted is preferably a rivet, indicated in dashed lines at 22 upon Fig. 2, this rivet extending through both the strip 13 of the bed 11 and the sector plate 21, and having at least its lower end, i. e. the end associated with the bed 11, countersunk so that it does not project beyond the lower face of the strip 13.

The end 23 of the strip 13 with which the sector plate 21 is associated, instead of being cut at right angles with the forward and 40 after edges of the strip, is cut at an angle of substantially forty-five degrees (45°), and the strip is widened adjacent the end 23 by an extension 24 from the after edge 26 of the strip, thereby presenting a relatively 45 large area of the upper surface of the strip 13 upon which the sector plate 21 is guided in pivotal motion about the axis of its pivot pin 22.

A bracket 27, arcuate in form, is secured 50 rigidly to the bed 11, and extends over the arcuate edge 28 of the sector plate 21, so that a pin 29 carried by the bracket 27 may be received within any one of a plurality of 55 holes 31 which are arranged in the sector plate 21 adjacent the edge 28 thereof. The arc within which the holes 31 are provided is drawn about the axis of the pivot pin 22 as a center, with the result that any one of the 60 holes 31 may be brought into registry with

the pin 29 by adjustment of the sector plate 21 about its pivot pin 22. The pin 29 is slidably mounted within a tubular housing 32 which is rigid with the upper surface of the bracket 27, and is provided with a head 33 70 whereby the pin 29 may be pulled upwards against the action of a coil spring 34 which is under compression between the top of the housing 32 and a pin 36 carried by the pin 29 within the housing. The parts are so 75 proportioned and arranged that when the pin 29 is thus pulled upwards its lower end will be retracted from the sector plate 21, permitting easy adjustment of the plate about its vertical axis, after which the pin 29 may 80 again be engaged within one of the holes 31 to hold the plate in selected position.

The saw guide, indicated in its entirety at 41, comprises an elongated strip, preferably of metal, which is bent back upon itself 85 along a transverse line 43 substantially midway between the ends of the strip, thus providing two parallel plates 44 and 46, spaced sufficiently to receive a saw therebetween. In order to impart rigidity to the plates 44 90 and 46, beads 47 are formed therein and extend longitudinally thereof, i. e., the beads 47 extend vertically downwards from adjacent the line 43 of bending of the strip 42. A transverse bead 48 is also formed in each 95 of the plates 44, 46 adjacent the upper edge thereof, and a bolt 49 extends through both plates 44, 46 at the central portions of the transverse beads 48. Inasmuch as the bolt 49 is spaced only slightly below the line of 100 juncture of the two plates 44 and 46, tightening of the nut 51 with which the bolt 49 is provided will result in pressing the plates 44 and 46 toward each other and into proper 105 guiding relationship with a saw disposed therebetween. This feature makes it possible 110 to hold the saw accurately and also to accommodate saws of different thickness. Preferably, both the forward and lower 115 edges 52 and 53, respectively, of both plates 44, 46 are flared outwards slightly, so as to facilitate reciprocation of the saw between the plates without damage to the set of the saw teeth.

The saw guide 41 is mounted upon the 120 sector plate 21 for adjustment about a horizontal axis with respect thereto, this being accomplished by means of a pair of spaced lugs 56 extending rigidly upwards from the sector plate 21 along its after radial edge, and another pair of lugs 57 extending rigidly from the plate 44 adjacent its lower edge, with a suitable pivot pin 58 extending through all the lugs 56 and 57. Means are 125 provided for releasably clamping the saw guide 41 in selected degree of angularity with respect to the sector plate 21. Preferably, this clamping means is in the form of an arcuate telescopic tube 61 comprising three sections 62, 63 and 64, each of which is 130

rectangular in cross section. The largest section 62 is made fast at its lower end to the sector plate 21, and the smallest section 64 is made fast at its outer end to the plate 44 of the saw guide 41. The intermediate section 63 is provided with arcuate slots 66 in its opposite sides, and bosses 67 are formed on the inner sides of the largest section 62 and are slidably received within the slots 66, so as to limit outward movement of the intermediate section 63 from the largest section 62. Similar bosses 68 are also formed on the outer surface of the smallest section 64, these bosses also being slidably received within the slots 66, so as to limit outward movement of the smallest section 64 with respect to the intermediate section 63. The parts are so proportioned and arranged that relative motion between the sections 62, 63 and 64 is resisted by the frictional engagement of the sections with each other. However, a set screw 69 is threaded through the largest section 62 adjacent its upper end, whereby the sections 64 and 63 may be firmly 25 clamped in completely telescoped position within the largest section 62.

I prefer to provide each of the holes 31 of the sector plate 21 with an indicium 71, preferably in the form of a numeral indicating 30 the degree of angularity of the saw guide 41 with the longitudinal axis of the bed 11 when the pin 29 is engaged within the associated hole 31. In this manner an operator is enabled to set the saw guide accurately, 35 so as to cut a timber 12 along a vertical plane disposed at a predetermined angle with respect to one of the edges of the timber. However, in view of the fact that the holes 31 must necessarily be spaced a material angular distance apart, I have provided 40 an auxiliary locking means in the form of a set screw 72 threaded through the bracket 27 in position to engage the upper surface of the sector plate 21 and clamp it in selected 45 position, even though none of the holes 31 lie in registry with the spring pressed pin 29.

If it be desired to cut a double angle the saw guide 41 may also be adjusted about the horizontal axis of the pin 58, as illustrated 50 on Figs. 4 and 5. Owing to the rigidity imparted to the plates 44 and 46 by means of the beads 47 and 48, tightening the nut 51 results in pressing the plates 44 and 46 toward 55 each other and into guiding engagement with a saw which is disposed between the plates, thereby insuring that a cut made with the saw will coincide in degrees of angularity with that face of the timber 12 with which 60 the flange 14 and/or extension 17 are in engagement, with the numeral 71 associated with the hole 31 with which the pin 29 is in engagement.

It is to be understood that the details of 65 the invention as herein disclosed, are subject

to alteration within the spirit or scope of the appended claims.

I claim:

1. A mitering guide comprising an elongated bed having a rigid flange extending downwards therefrom along its forward edge, a plate mounted adjacent an end of said bed for pivotal movement about a vertical axis, saw-guiding means carried by said plate, means for releasably clamping said plate to said bed with said guiding means in selected angular relation with said bed, and extensions removably secured to said bed at spaced intervals therealong, the after faces of said extensions being flush with the after 80 face of said flange.

2. In a mitering guide, saw-guiding means comprising an elongated strip bent back upon itself along a transverse line to present a pair of substantially parallel plates joined along 85 their upper edges, each of said plates having beads extending longitudinally thereof to increase their rigidity, and means adjacent the upper edges of said plates for pressing the plates toward each other into guiding engagement with a saw disposed therebetween.

3. In a mitering guide, saw-guiding means comprising an elongated strip bent back upon itself along a transverse line to present a pair of substantially parallel plates joined along 95 their upper edges, each of said plates having beads extending longitudinally thereof to increase their rigidity, a bolt extending through both plates and spaced slightly below their joined upper edges, and a nut 100 threaded onto said bolt and adapted to press said plates toward each other into guiding engagement with a saw disposed therebetween.

4. In a mitering guide, saw-guiding means comprising a strip bent back upon itself to present a pair of parallel plates joined along their upper edges, each of said plates having beads extending longitudinally thereof to increase their rigidity, a transverse bead formed 110 in each plate adjacent the joined edges thereof, a bolt extending through said transverse beads, and a nut threaded onto said bolt and adapted to press said plates toward each other into guiding engagement with a saw disposed 115 therebetween.

In testimony whereof I have signed my name to this specification.

THOMAS BURDICK.
